ALEXANDER H. WELKER, OF BERLIN, ONTARIO, CANADA.

MOTOR-WINDING MECHANISM.

1,024,237.

Specification of Letters Patent. Patented Apr. 23, 1912.

Application filed May 5, 1911. Serial No. 625,144.

To all whom it may concern:

Be it known that I, ALEXANDER H. WELKER, a subject of the King of Great Britain, residing at Berlin, in the county of Waterloo, Province of Ontario, Canada, have invented certain new and useful Improvements in Motor-Winding Mechanism, of which the following is a specification.

This invention relates to talking-machines and is directed to the provision of certain improvements in machines of this character with respect to the mechanisms for winding the motors thereof.

Talking-machines are commonly provided with spring-actuated motors for rotating the record-tablets thereof, and these motors have winding-shafts projecting close to or beyond the exterior of the casings. In practice, it is common to wind the motor by applying a winding-handle to the end of this shaft. If such a winding-handle be removed from the shaft, it is apt to become misplaced, thus causing considerable inconvenience when it is necessary to rewind the motor. If, on the other hand, the winding-handle be allowed to remain in place upon the end of the winding-shaft, it detracts from the appearance of the machine as a whole, particularly in the case of a machine of the so-called "hornless" type, having a handsomely finished casing.

This invention involves the provision of a winding mechanism for a talking-machine motor, which, without detaching it, may be moved to inoperative position within the casing of the instrument or caused to take an operative position exterior to the casing of the instrument, at will. With this construction, the motor may be wound by turning the handle when the latter is in its operative position, and thereafter the handle may, without detaching it from the winding-shaft, be moved within the casing and a door in the casing closed over it, so that the winding mechanism is entirely concealed.

I have illustrated the preferred embodiment of my invention in the accompanying drawings, in which—

Figure 1 is a front view of the upper portion of a talking-machine, broken away and sectioned in part; Fig. 2 is a top view of a portion of the machine, broken away and sectioned in part; and Figs. 3 and 4 are detail views hereinafter referred to.

The drawings illustrate a machine of the "hornless" type, in which the sound-conveying and -amplifying horn extends down-

wardly and through the casing of the instrument.

1 indicates the casing, having a hinged cover 2, which normally conceals the turn-table, the sound-record thereon, the reproducing mechanism and the pivoted tone-arm. The tone-arm connects with a tapering sound-conveying and -amplifying device 3, which extends through the casing of the instrument from the rear to the front thereof. The motor is mounted within the casing, above the conveyer 3 and below the turn-table within the cover 2. The winding-shaft of this motor is shown at 4. In the present instance, its end passes through a partition 5 within the casing 1. A support 6 is secured upon this end of the winding-shaft 4. Preferably, this end of the winding-shaft is threaded, as shown in Fig. 3, and the support 5 has a threaded opening in one end thereof, adapted to fit upon the threaded end of shaft 4. When the support is in position upon shaft 4, it is secured against rotation relatively thereto by a pin 7 or other suitable means. Beyond the end of the shaft 4, the support 6 has a longitudinal slot therein to receive the end of the winding-crank 8, whose end is provided with a handle 9. The walls on opposite sides of the slot in the support 6 are provided with slots 10 extending lengthwise of the support, and these slots receive the ends of a pin 11 passing through the end of the handle 8. In this way, the handle may move relatively to the support 6 in the direction of the length of the support an amount limited by the length of the slots 10. A helical spring 12 encircles the support 6, one end thereof being secured to the support, as by means of the screw 13. At its other end, the spring engages the ends of pin 11, so that the spring constantly exerts a tension tending to move pin 11 and handle 8 to the left in Fig. 3, that is, toward the winding-shaft 4. The end of the support 6 is curved, as shown at 14, to provide cam-surfaces on opposite sides of the slot, with which surfaces the ends of a pin 15 coact, this pin extending through the crank 8. At the center of these curved surfaces, are notches, as shown in Fig. 3, to receive the ends of pin 15.

Figs. 1 and 3 show the operative position of the winding-handle 8. In this position, the pin 15 coacts with the walls of the notches in the curved end of support 6, so that turning the handle 9 will turn sup-

port 6 and with it the winding-shaft 4, to which it is secured. After the motor of the talking-machine has been wound up, the crank 8 is brought to a substantially horizontal position and pulled outwardly slightly, against the tension of spring 12, until the pin 15 is out of the notches with which it coacts. Such movement of crank 8 is permitted by the slots 10 which receive the ends of pin 11. When this movement of the crank has been effected, the latter is swung about the pin 11 as a pivot, and as the pin 15 moves around the curved surface at the end of support 6 the spring 12 will move the crank relatively to the support 6 until the pin 11 has reached the inner end of the slots 10. The handle may thus be turned to the inoperative position, in which it is shown in Fig. 2, in which position it lies wholly within the casing 1 of the machine. The opening in the wall of the casing through which the crank 8 is so moved, may be closed by means of a hinged door 16, as shown in Fig. 1.

In turning the crank from the inoperative to the operative position, the ends of pin 15 engage the curved surfaces 14 and those surfaces act as cams, moving the crank in a direction to extend spring 12 until pin 15 comes opposite its coacting notches, whereupon the handle 8 is moved by spring 12 to carry pin 15 into the notches with which it coacts.

Having now described my invention, what I claim as new therein and desire to secure by Letters Patent is as follows:—

1. In a talking-machine, the combination of a casing having a compartment therein, a door closing said compartment, a winding-shaft projecting into said compartment, a winding-crank applied to said shaft, and means permitting movement of said crank to an inoperative position within said casing and permitting closure of said door or to an operative position in which it extends beyond said casing, substantially as set forth.

2. In a talking-machine, the combination of a casing having a compartment therein, a door closing said compartment, a winding-shaft whose end projects into said compartment, a winding-crank pivotally connected to said end of the shaft and movable relatively to the shaft to inoperative position in which it lies within the casing and permits closure of said door or to an operative position in which it extends beyond said casing, and means for securing the crank against movement relatively to the shaft when the crank is in operative position, substantially, as set forth.

3. In a talking-machine, the combination with a casing having a compartment there-

in, a door closing said compartment, a winding-shaft whose end projects into said compartment, a winding-crank pivotally connected to said end of the shaft and movable relatively thereto to inoperative position within the casing and permitting closure of said door or to operative position in which it extends beyond the casing, said crank when in operative position extending from said shaft in a radial direction beyond the wall of said compartment, and means for securing the crank against movement relatively to the shaft when the crank is in operative position, substantially as set forth.

4. In a talking-machine, the combination of a casing having a compartment therein, a door closing said compartment, a winding-shaft whose end projects into said compartment, and a crank connected to said end of the shaft and movable relatively thereto in the direction of the length of the shaft and about an axis transverse to said length, the movement of the crank about said axis carrying the crank to inoperative position within the casing and permitting closure of said door or to operative position projecting through said opening and beyond the casing, and the movement of the crank in the direction of the length of the shaft coupling the crank to or uncoupling it from the shaft, substantially as set forth.

5. In a talking-machine, the combination of the winding-shaft, the crank, the walls on the shaft between which the handle is pivotally mounted by a pin-and-slot connection, so that the crank may move relatively to the winding-shaft in the direction of the length of the shaft in addition to winding shaft, the pin on the crank coacting with notches in said walls to prevent turning of the crank relatively to the winding-shaft, and the spring to hold said pin yieldingly in connection with said notches, substantially as set forth.

6. In a talking-machine, the combination of the winding-shaft, the crank, the walls on said shaft having curved ends with notches formed therein, said crank being pivotally mounted between said walls by a pin-and-slot connection, a pin on said crank adapted to coact with said curved ends and notches, and a spring acting on said crank to carry said pin into coaction with said curved ends and notches, substantially as set forth.

This specification signed and witnessed this 24th day of April, 1911.

ALEXANDER H. WELKER.

Witnesses:

ARTHUR B. POLLOCK,
J. A. SELLENE.

It is hereby certified that in Letters Patent No. 1,024,237, granted April 23, 1912, upon the application of Alexander H. Welker, of Berlin, Ontario, Canada, for an improvement in "Motor-Winding Mechanism," an error appears in the printed specification requiring correction as follows: Page 2, line 102, after the words "addition to" the words *moving about its pivotal connection to the* should be inserted; and that the said Letters Patent should be read with this correction therein that the same may conform to the record of the case in the Patent Office.

Signed and sealed this 21st day of May, A. D., 1912.
